E. C. HELWIG

TELEPHONE EXCHANGE SYSTEM

Filed Dec. 31, 1921

UNITED STATES PATENT OFFICE.

EUGENE C. HELWIG, OF HACKENSACK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 31, 1921. Serial No. 526,226.

To all whom it may concern:

Be it known that I, EUGENE C. HELWIG, a citizen of the United States, residing at Hackensack, in the county of Bergen, State 5 of New Jersey, have invented certain new and useful Improvements in Telephone-Exchange Systems, of which the following is a full, clear, concise, and exact description.

10 This invention relates to telephone exchange systems and more particularly to such systems in which connections between telephone lines terminating at manual and automatic exchanges are established by an 15 operator by way of cord and trunk circuits over which automatic switches are controlled by the operator for effecting connections between the lines terminating at the manual and automatic exchanges.

20 One object of the invention is to simplify and improve systems of this character which employ a full metallic dialing circuit for controlling the automatic switches.

A further object of the invention is to 25 control the character of a trunk circuit and the association of the supervisory bridges therewith by changing the direction of current flow over a conductor associated with the trunk circuit.

30 To carry out the objects of the invention a key only is provided in each cord circuit for rendering the sender individual to a cord circuit. The trunk circuit extending from the operator's position to the automatic exchange is provided with means which normally prevent or block the flow 35 of direct current, from the manual to the automatic exchange or vice versa, when the cord circuit is connected to the trunk circuit.

40 A pair of bridges, one for each side of the blocking means, is provided in the trunk circuit for controlling the supervisory apparatus in the cord circuit. The insertion of a plug of the cord circuit into a jack of 45 the trunk circuit closes a sleeve circuit over which the connection of the bridges across the trunk circuit is controlled. An actuation of the key then reverses the flow of current over the sleeve circuit causing the 50 short circuiting of the blocking means and the connection of the sender across the talk-

ing conductors of the trunk circuit thereby establishing the through dialing circuit. By providing this reversal of current when the key is actuated, the bridges are held 55 disconnected, the blocking means are short circuited and a normal busy test is given during the dialing period. The restoration of the key to normal after dialing disconnects the sender from the cord circuit and 60 again reverses the flow of current in the sleeve causing the connection of the bridges to the trunk circuit and the removal of the short circuit from the blocking means. The 65 bridges now function when the called party answers and hangs up, to actuate a supervisory signal at the operator's position.

For a more complete understanding of this invention reference may be had to the following description and to the accompanying 70 drawing which illustrates one embodiment of the invention.

There is shown in the drawing a telephone line A which terminates at the manual exchange where it may be connected 75 with a cord circuit B in any suitable and well known manner. The calling end of the cord circuit B may be connected with a trunk circuit C extending from the manual to the automatic exchange, at which are 80 provided the usual selector and connector switches for effecting connection between the trunk circuit and the telephone lines. A connector switch is schematically indicated at K. It will be understood, however, that 85 any desired number of selector switches may be connected between the trunk circuit C and the connector switch K. The apparatus shown to the left of the dotted line 1 is located at the manual exchange and to the 90 right thereof at the automatic exchange.

The subscriber at telephone line A having initiated a call and the answering end of the cord circuit B having been associated therewith in any well known manner, the 95 operator actuates listening key 5, connecting the operator's telephone set in the circuit so that the operator may converse with the calling subscriber to ascertain the number of the line with which connection is desired. Assuming that connection is desired with 100 telephone line D, which terminates at the

automatic exchange, the operator inserts calling plug 6 of the cord circuit B into jack 7 of the trunk circuit C. Calling supervisory lamp 8 and sleeve relay 9 are thereupon operated over a circuit extending from grounded battery lamp 8, resistance 43, sleeves of plug 6 and jack 7, inner left-hand normal contacts of relay 12, and winding of relay 9 to ground.

- 10 The operator may now actuate the dialing key 41 for the purpose of connecting the sender or dial S to the cord circuit, whereupon relays 11, 12, 13 and 14 are successively energized. Relay 11 is operated 15 over a path extending as follows: ground, normal contacts of polarized relay 19, right normal contacts of relay 13, winding of relay 11, lower winding of coil 10, right-hand normal contacts of relay 12, tips of jack 7 20 and plug 6, upper alternate contacts of key 41, contacts 44 of dial S, winding of polarized relay 45, contacts 46 of key 41, rings of plug 6 and jack 7, upper winding of coil 10, and left-hand normal contacts of relay 25 25 13 to grounded battery. Relay 11, in operating, completes a circuit for relay 12 over a path as follows: grounded battery, winding of relay 12, contacts of relay 11, sleeves of jack 7 and plug 6, lowermost contacts of 30 key 41 and resistance 42 to ground. Relay 12, in operating, locks through its inner left-hand alternate contacts and through resistance 42 under control of the key 41. Lamp 8 which was lighted over a circuit 35 including normal contacts of relay 12 remains lighted over a circuit including resistance 42, when the key 41 is actuated. The resistance values of relays 12 and 9 and resistances 42 and 43 are so chosen that the 40 sleeve resistance during the time key 41 is actuated (or during the dialing period) is practically the same as when the key 41 is in normal position so that a substantially uniform busy test is given to the operator, 45 regardless of the position of the dialing key. The operation of relay 12 renders the talking conductors of the trunk circuit C conductively continuous, by short circuiting the condenser 22 by a direct current path 50 through its inner right-hand alternate contacts and by short circuiting the condenser 23 by a direct current path through its outer left-hand alternate contacts. Relay 12, in operating, also completes a circuit 55 through its outer right-hand contacts for relay 13. Relay 12, in operating, also opens the energizing circuit for relay 9 which releases. Relay 13, in operating, prepares a bridge for the inner section of the trunk 60 circuit, said bridge extending from the ring talking conductor of the inner section of trunk C, through the upper winding of coil 10, outer and inner left-hand alternate contacts of relay 13, lower winding of coil 10, inner right-hand normal contacts of

relay 12 to the tip talking conductor of the inner section of trunk C. This bridge, being open at the contacts of relay 12, performs no function at the present time. Relay 13, in operating, also completes a circuit 70 for slow-to-release relay 14 over a path extending from ground, normal contacts of polarizer relay 19, right-hand alternate contacts of relay 13, and winding of relay 14 to grounded battery. For the purpose of indicating that relay 14 is of the slow-to-release type, an arrow pointed in the direction in which the armature is slowly moved, is shown. Relay 14, in operating, prepares 75 a bridge for the outer section of the trunk circuit C, said bridge extending from the ring conductor of the outer section of trunk C, outer left-hand normal contacts of relay 12, outer contacts of relay 14, winding of polarized relay 19, coil 18 to the tip talking conductor of the outer section of the trunk circuit C. This bridge, being open at the contacts of relay 12, performs no function 80 at the present time.

It will thus be seen that as soon as the dialing key is actuated, a loop dialing circuit free from bridges is established, extending from the operator's position over the connected cord and trunk circuit to the automatic exchange. A non-numerical switch (not shown) may then be actuated to extend the connection to a connector switch, such as K, whereupon impulse responsive relay 25 of the connector K will be energized over a path extending from ground, left-hand winding of relay 25, left-hand normal contacts of relay 26, outer left-hand alternate contacts of relay 12, ring contacts of jack 7 and plug 6, contacts 46 of key 41, winding of polarized relay 45, contacts 44 of dial S, upper alternate contacts of key 41, tip contacts of plug 6 and jack 7, inner right-hand alternate contacts of relay 12, inner normal contacts of relay 26, and right-hand winding of relay 25 to grounded battery.

As soon as the dial is moved off normal the contacts 60 are closed and remain closed until the dial returns to normal position. The closure of contacts 60 short circuits relay 45 so as to reduce the resistance of the dialing path. The operator by actuating the dial S may set the switch K on the line D of the desired subscriber after which the bell at the station of line D may be actuated in the well known manner. The subscriber of station D in removing the receiver from the switchhook causes the energization of relay 26. Relay 26 in operating reverses the battery connections to the talking conductors of the trunk circuit whereby the polarized relay 45 which is bridged across the conductors of the cord circuit B is energized and closes its contact. The closing of this contact causes the energization of relay 49, which is common to an operator's posi-

tion, over an obvious circuit. Relay 49 in operating causes a tone to be transmitted to the operator's telephone set over a path extending from grounded battery, inter-
 rupter 50, inner alternate contacts of relay 49, winding 52 of coil 55 and thence in parallel, one path extending through winding 54 and the other path extending through winding 53 of coil 55 and receiver 51 through the outer alternate contacts of relay 49 to ground. This tone is for the purpose of audibly informing the operator that she has failed to restore the dialing key. Upon hearing such tone the operator will immediately restore dialing key 41 to normal. It will thus be seen that if the operator answers a second call at her position and fails to restore the dialing key utilized in completing a preceding call, she will receive an audible signal as soon as the called station of the preceding connection answers. The operation will now be described in the case where the operator restores the dialing key 41 to normal as soon as the dialing operation is complete. The restoration of key 41 to normal opens the locking circuit for relay 12 whereupon it releases. Relay 12 in releasing, opens the direct current paths around the condensers 22 and 23 so that the inner and outer sections of the trunk circuit for this current are conductively separated and opens the circuit for relay 13, which releases and closes the original energizing circuit for relay 9, which operates. The restoration of key 41 to normal has therefore again reversed the flow of current over the sleeve circuit. Relay 14 being of the slow-to-release type does not retract its armature when relay 13 deenergizes because a substitute circuit to ground through the contacts of relay 9 is provided and it thus holds the bridge across the outer section of the trunk circuit when the dial key is restored to normal. Supervisory lamp 8 remains lighted over the circuit previously traced. As soon as the called station answers, polarized relay 19 operates over a circuit extending from grounded battery, right hand winding of relay 25, outer left-hand alternate contacts of relay 26, ring of trunk C, outer left normal contacts of relay 12, outer contacts of relay 14, winding of polarized relay 19, coil 18, tip of trunk C, inner alternate contacts of relay 26, and left-hand winding of relay 25 to ground. Relay 19 in operating completes a circuit for relay 13 over a path extending from grounded battery, winding of relay 13 and contacts of relay 19 to ground. Relay 13 in operating connects the bridge, previously traced, across the inner section of the trunk circuit thereby causing the energization of relay 40 and the extinguishment of lamp 8 in the well known manner, to indicate to the operator that the called party

has answered. At the conclusion of conversation, the subscribers may restore their receivers to the switchhook. The restoration of the receiver to the switchhook on telephone line D causes the deenergization of reversing relay 26, whereupon the connection of battery to the talking conductors of the trunk circuit is reversed causing the release of polarized relay 19. Relay 19 in releasing opens the circuit for relay 13, which releases. Relay 13 in retracting its armatures opens the bridge across the inner section of the trunk circuit causing the deenergization of supervisory relay 40 and the lighting of supervisory lamp 8 which now serves as a disconnect signal to the operator at the manual office. The operator may thereupon disconnect the plug 6 from the jack 7 whereupon all operated apparatus associated with the calling end of the link circuit B and with the trunk circuit C is released and restored to normal position.

What is claimed is:

1. In a telephone exchange system, a plurality of subscribers' lines, means including a cord circuit and a connected trunk circuit for establishing a connection between two of said lines, an impulse sender for transmitting impulses over the two sides of said trunk circuit in series, an inductive device in the trunk circuit, a key for connecting said impulse sender to the cord circuit, a relay, and means for energizing said relay during the actuation of said key to provide a path around said inductive device. 100

2. In a telephone exchange system, a plurality of subscribers' lines, means including a cord circuit and a connected trunk circuit for establishing a connection between two of said lines, an impulse sender for transmitting impulses over two sides of said trunk circuit in series, an inductive device in the trunk circuit, a key for connecting said impulse sender to the cord circuit, a relay, and a circuit completed by the actuation of said key to energize said relay to provide a path around said inductive device. 105

3. In a telephone exchange system, a plurality of subscribers' lines, means including a trunk circuit and a connected cord circuit for establishing a connection between two of said lines, an impulse sender for transmitting impulses over the two sides of the trunk circuit in series, condensers in the trunk circuit, a relay, and a key for controlling said relay to short circuit said condensers during the operation of said key. 115

4. In a telephone exchange system, a trunk circuit, a cord circuit, a supervisory signal in the cord circuit, condensers in the trunk circuit conductively dividing it into inner and outer sections, a bridge for the outer section, an impulse sender for the cord circuit, a key for connecting the sender in serial relationship with the talking conduc- 125 130 136

tors of the trunk circuit, means in the trunk circuit responsive to the actuation of the key for establishing a direct current path around the condensers, and means responsive to the restoration of the key for connecting said bridge to said trunk circuit to control said signal.

5. In a telephone exchange system, a trunk circuit, condensers in said trunk circuit, a cord circuit connected to the trunk circuit, a signal in the cord circuit, a bridge for the trunk circuit for controlling said signal, a dial for sending impulses over two sides of the trunk circuit in series, a key in the cord circuit, and means responsive to the actuation of said key for short circuiting said condensers and for connecting said dial to said cord circuit.

6. In a telephone exchange system, a trunk circuit, condensers in said trunk circuit, a cord circuit connected to the trunk circuit, a signal in the cord circuit, a bridge for the trunk circuit for controlling said signal, a dial for sending impulses over two sides of the trunk circuit in series, a key in the cord circuit, means responsive to the actuation of said key for short circuiting said condensers and for connecting said dial to said cord circuit, and means responsive to the restoration of said key for connecting said bridge to said trunk circuit.

7. In a telephone exchange system, a trunk circuit, condensers in said trunk circuit, a cord circuit connected to the trunk circuit, a signal in the cord circuit, a bridge for the trunk circuit for controlling said signal, a dial for sending impulses over two sides of the trunk circuit in series, a key in the cord circuit, means responsive to the actuation of said key for short circuiting said condensers and for connecting said dial to said cord circuit, and means responsive to the restoration of said key for connecting said bridge to said trunk circuit and for removing said short circuits from said condensers.

8. In a telephone exchange system, a trunk circuit, condensers in said trunk circuit, a cord circuit connected to the trunk circuit, a signal in the cord circuit, a bridge for the trunk circuit for controlling said signal, a dial for sending impulses over two sides of the trunk circuit in series, a key in the cord circuit, and means controlled by said key over the sleeve of the cord and connected trunk circuit for controlling the short circuiting of said condensers.

9. In a telephone exchange system, a trunk circuit, condensers in said trunk circuit, a cord circuit connected to the trunk circuit, a signal in the cord circuit, a bridge for the trunk circuit for controlling said signal, a dial for sending impulses over two sides of the trunk circuit in series, a key in the cord circuit, and means controlled by

said key over the sleeve of the cord and connected trunk circuit for controlling the short circuiting of said condensers and for controlling the connection of said bridge to said trunk circuit.

10. In a telephone system, a cord circuit, a trunk circuit, a dial for sending impulses over said trunk circuit, a signal, a bridge associated with the trunk for controlling said signal, a key in the cord for connecting the dial therewith, means operative responsive to the interconnection of said cord and trunk for causing said signal to assume a certain condition, means responsive to the actuation of said key for changing the condition of said bridge, and means operative responsive to the restoration of said key for changing the condition of said signal.

11. In a telephone exchange system, a cord circuit, a trunk circuit, a talking circuit and a test circuit established by the connection of said cord circuit and said trunk circuit, a dial for sending impulses, means including the test circuit for connecting said dial to send impulses over two talking conductors of said trunk circuit in series, means for establishing a test potential over said test circuit when the cord circuit is connected to the trunk circuit, and means for maintaining said test potential practically constant during the dialing and talking periods.

12. In a telephone exchange, a trunk circuit, a talking and a control circuit for said trunk circuit, a source of current included in the control circuit, a test contact, means for reversing the flow of current in the control circuit, and means for maintaining the potential of the test contact substantially constant.

13. In a telephone exchange system, a trunk circuit comprising a pair of talking conductors, a condenser in each of the talking conductors, a cord circuit connected with the trunk circuit, an impulse sender, a key for connecting the sender to the cord circuit, a relay in the trunk circuit operating in response to the actuation of the key for establishing a direct current path around each of the condensers, and an impulse relay controlled by the sender over a circuit including the direct current paths around the condensers.

14. In a telephone exchange system, a trunk circuit comprising a pair of talking conductors, a condenser in each of the talking conductors, a cord circuit connected with the trunk circuit, an impulse sender, a key for connecting the sender to the cord circuit, a relay in the trunk circuit operating in response to the actuation of the key for establishing a direct current path around each of the condensers, and means controlled by the restoration of the key for removing the direct current path around the condensers.

15. In a telephone exchange system, trunk conductors, a bridge, a third conductor, a source of current associated with said third conductor, means for reversing the direction of current flow over the conductor, and means responsive to the reversed current flow to control the association of the bridge with the trunk conductors.
16. In a telephone exchange system, inductively continuous trunk conductors, a third conductor, a source of current associated therewith, means for reversing the direction of flow of current over said third conductor from the source, and means responsive to the flow of current in the reversed direction for rendering the trunk conductors conductively continuous.
17. In a telephone exchange system, a trunk circuit, inner and outer sections therefore, a plurality of bridges, means interconnecting the sections, a conductor, a source of current connected thereto, means responsive to a flow of current over the conductor from the source to change the character of the means interconnecting the sections, means for changing the character of the current flowing over the conductor, means responsive to the changed current flow to associate one of the bridges with the outer section of the trunk circuit, and means included in the bridge to control the association of another of the bridges with the inner section.
18. The method of controlling automatic switches and providing supervision over inductively interconnected sections of a trunk circuit extending from a manual to an automatic switchboard which comprises transmitting current of one character over a conductor to conductively interconnect the sections, transmitting impulses over the conductively interconnected sections to control the switches and transmitting current of

a different character over the conductor to conductively separate the sections.

19. In a telephone exchange system, a trunk circuit comprising a pair of talking conductors, an impulse relay connected to one end of said trunk circuit, a cord circuit connected to the other end of said trunk circuit, condensers in said trunk circuit, an impulse relay, an impulse sender associated with said cord circuit, a key, and means controlled by the actuation of said key for connecting said sender to said cord circuit and for short circuiting said condensers to connect said sender in series relationship with said relay.

20. In a telephone exchange system, an inductively continuous trunk circuit, a cord circuit connected thereto, an impulse sender, a key only for connecting the sender to the cord circuit and for rendering said trunk circuit conductively continuous, an impulse relay, and a series circuit including two sides of said trunk circuit and said sender for controlling said relay.

21. In a telephone exchange system, a trunk circuit comprising a pair of talking conductors, a source of direct current connected thereto, a cord circuit connected to said trunk circuit, a source of direct current connected thereto, condensers in said trunk circuit for separating said sources, an impulse sender on one side of said condensers, an impulse relay on the other side of said condensers, a key, and means controlled by the actuation of said key for connecting said sender to said trunk circuit and for short circuiting said condensers to place said relay under control of said sender.

In witness whereof, I hereunto subscribe my name this 27th day of December A. D., 1921.

EUGENE C. HELWIG.
